(57) **CLAIM**

The ornamental design for a handle for a panel of electrical equipment, as shown and described.

DESCRIPTION

FIG. 1 is a front view of a handle for a panel of electrical equipment showing my new design, the rear view being a mirror image thereof;

FIG. 2 is a top view thereof;

FIG. 3 is a bottom view thereof;

FIG. 4 is a right side view thereof;

FIG. 5 is a left side view thereof;

FIG. 6 is a sectional view thereof, being taken along line A—A of FIG. 2, inside of the article being simplified;

FIG. 7 is a sectional view thereof, being taken along line B—B of FIG. 2, inside of the article being simplified; and,

FIG. 8 is a front view thereof, in elevation of the lever.

The broken lines shown in FIGS. 1-8 are for illustrative purposes only and form no part of the claimed design.
